DEMAND REGISTER

Robert H. Lewis, North Arlington, and Paul G. Adams, Bloomfield, N. J., assignors to Westinghouse Electric & Manufacturing Company, East Pittsburgh, Pa., a corporation of Pennsylvania

Application July 1, 1938, Serial No. 217,024

22 Claims.

(Cl. 171—34)

This invention relates to registers and it has particular relation to reset mechanisms for registers of the maximum demand type.

In Patent No. 2,047,376 to Lewis et al., a maximum demand meter of the indicating type is disclosed. Meters of this type have an indicating member which is actuated during a billing period, usually one month, to a position corresponding to the maximum demand for the billing period. At the end of the billing period, it is customary to note the quantity indicated after which the indicating hand is manually returned to an initial or zero position. This procedure is open to several objections. Once the indicating hand has been restored to its initial position, all record of the maximum demand for that particular period is lost, and no check is available on the person who has noted such maximum demand. Moreover, on most manual resets of this type, it is possible for the indicating hand to be reset to a position other than the zero position.

The difficulties experienced with meters of the type shown in the aforesaid patent may be overcome by providing an independent register for the maximum demand reading. Such a register would have an amount added thereto for each billing period corresponding to the maximum demand for that billing period. In order to eliminate possible inaccuracies from the manual reset of the register, it is preferable to provide a motor-driven reset which may be actuated periodically at the end of each billing period. Since meters to which maximum demand registers ordinarily are applied have little power available for driving the register, and since such registers must be capable of long service without attention, some ingenuity is required in the design of a suitable register.

In accordance with our invention, a separate maximum demand or cumulative register is provided which is actuated once at the end of each billing period to preserve the maximum demand for that period. This register is actuated by motive means which is coupled and uncoupled thereto by means of gears. This avoids the inaccuracies and power demands of clutches.

It is, therefore, an object of our invention to provide a simple and reliable register having a motor reset attachment.

It is a further object of our invention to provide a cumulative type of maximum demand register wherein gears are employed for coupling and uncoupling a reset motor thereto.

It is a further object of our invention to provide a reset device for transferring a demand

indication to a register which cannot be actuated when no demand indication is available for transfer to the register.

It is a further object of our invention to provide an interval clutch for a demand register which has a positive release.

It is a still further object of our invention to provide a demand register with a clutch having a uniform slip resistance when engaged.

10 Further objects of our invention will be apparent from the following description taken in conjunction with the accompanying drawing, in which:

Figure 1 is a view in perspective of a register embodying our invention;

Figs. 2 and 3 are exploded perspective views showing two positions of the control levers employed for resetting our register;

Fig. 3a is a detail view in perspective showing 20 a spring construction for a reset latching lever.

Fig. 4 is a detail view partly in cross-section of a maximum demand indicating assembly; and

Fig. 5 is a detail view showing the gear coupling between the maximum demand indicator 25 and the register.

Referring to the drawing, the register shown in Fig. 1 is based very largely on that shown in the aforesaid patent. For convenience, the parts shown in Fig. 1 which correspond to those disclosed in the aforesaid patent are provided with similar reference characters. Briefly, the register illustrated comprises a disc 2 of an induction watthour meter which drives indicating pointers 8 through a shaft 3, worm gear and worm wheel 35 5, and a suitable gear train 6. The integrating pointers 8 may be employed for indicating kilowatt-hours on dials formed on a face plate 10 in a customary manner.

In order to indicate the maximum demand for 40 a billing period, a pusher arm 20 is attached to a sleeve 22, which is periodically rotated. The sleeve 22 and a gear 24 are mounted on a shaft 25 and constitute parts of a releasable clutch. The gear 24 is driven from the disc 2 by means 45 of a gear 26 which is coupled to the disc 2 through the gear train 6. At periodic intervals, usually every thirty minutes, the clutch is released to free the sleeve 22, which is returned to an initial or zero setting by means of a spiral spring 28 which has one end attached to the sleeve 22 and the remaining end attached to a stationary part 50 of the register. Consequently, the maximum rotation of the sleeve 22 and the pusher arm 20 carried thereby represents the maximum demand 55 for a thirty-minute period.

The release of the clutch after each demand interval is effected by means of a clutch release lever 44 which rocks on opposed pivots 45 (only one of which is shown). In order to time the actuation of the lever 44, a constant speed motor 50 is provided which may conveniently be of the hysteresis type. This motor, through a suitable enclosed speed reducing gearing 52, drives a shaft 54 which may rotate, for example, at one revolution per minute, and which, through gearing 58, rotates a shaft 60 and a sleeve 70 at different rates. For example, if a thirty-minute period is employed, the shaft 60 may be rotated one revolution each thirty minutes, and the sleeve 70 may be rotating twelve times as rapidly. At its lower end, the shaft 60 carries a disc 62 on which a cam lever 64 is pivotally mounted. A cam disc 72 is mounted on the sleeve 70 adjacent the cam lever 64. Once during each revolution of the disc 62 the actuating portion of the cam lever is adjacent the clutch release lever 44. At this moment, the high portion of the cam 72 strikes the actuating portion of the cam lever 64 and moves it sharply against the clutch release lever 44 to release the clutch for a short interval merely sufficient to permit the return of the sleeve 22 and pusher arm 20 to their initial positions. For test purposes, an overrunning clutch 90 preferably is included between the motor and the clutch release assembly. Further details of the construction thus far described will be found by reference to the aforesaid patent.

In order to preserve an indication of the maximum position to which the pusher arm 20 is rotated in a thirty-minute interval, a sleeve 100 is mounted freely on the shaft 25 in coaxial alignment with the sleeve 22. The sleeve 100 carries an arm 101 provided with a pin 102 in the path of movement of the pusher arm 20. As the pusher arm 20 rotates, it engages the pin 102 and carries the sleeve 100 with it. The sleeve 100 is provided also with a gear 103 which preferably carries an indicating pin 104. This indicating pin projects through an opening 105 in the register face 10, the opening being shown in dotted lines in Fig. 1. Consequently, as the pusher arm 20 rotates, the pin 104 will be carried to a position corresponding to the maximum rotation of the pusher arm. If desired, a scale may be provided on the register face 10 for indicating the demand corresponding to any movement of the pin 104. When the pusher arm 20 returns to its initial or zero position at the end of one of its thirty-minute intervals, the pin 104 remains in the position to which it has been rotated, and over a billing period, say, a thirty-day period, indicates the maximum thirty-minute demand for the billing period.

If the pin 104 were returned to an initial or zero position at the end of a billing period, no record ordinarily would remain of the position from which it was moved. In order to provide such a record, we include in our register a second set of integrating pointers 106 which may be similar to those 8 employed for indicating kilowatt-hours. At the end of each billing period, the integrating pointers 106 are coupled to the pin 104 and are advanced in accordance with the resetting movement of the pin by a mechanism which now will be described.

As above noted, the pin 104 is carried on a gear 103. This gear meshes with another gear 107 which is fixed to a shaft 108. Fixed on the shaft 108 is a gear 109 which meshes with a gear 110 (Fig. 5) carried by a sleeve 111, the sleeve being

free to rotate on a shaft 112. The sleeve 111 also carries a gear 113. A second sleeve 114 on the same shaft 112 carries two gears 115 and 116 thereon. The gears 113 and 115 are adjacent each other and are of the same size. The gear 116 is connected through a gear 117 to the first shaft 118 of the maximum demand integrating pointer unit.

It will be noted that the gear 113 moves in accordance with movements of the pin 104, whereas the gear 115 moves in accordance with movements of the integrating pointers 106. Immediately prior to the resetting of the pin 104 and its associated mechanism at the end of a billing period, these two gears 113 and 115 are coupled by means of an elongated pinion 119 which is moved into engagement therewith. As a result of this movement, the pin 104, through the gears 103, 107, 109, 110, 113, 119, 115 and 116, is coupled to the integrating pointers 106, and any movement thereof is transmitted to the integrating pointers and retained thereby. At the end of the reset operation, the pinion 119 is moved out of engagement with its associated gears.

While the foregoing operations could be carried out manually, it is preferable to provide an automatic reset and to drive the reset mechanism from the timing motor 50. For this purpose, a crown gear 120 is coupled to the motor 50 through suitable gears 121 and 122 and one of the gears of the gear train 58 which is connected to the motor 50 through the gearing 52. During a resetting operation, this crown gear is connected to the integrating pointers 106 and the indicating pin 104 through gears 123 and 124, which are fixed on a common shaft 125. The gear 124 meshes with a gear 126, which is fixed to the shaft 108, and which through the shaft 108 rotates the gears 107 and 109. These gears in turn communicate movement to the indicating pin 104 and the integrating pointers 106.

If the gear 123 were coupled to the crown gear 120 before the pinion 119 were moved into engagement with its associated gears, movement would be transmitted to the indicating pin 104 before movement could be transmitted to the integrating pointers 106. This would result in an inaccuracy in the amount indicated by the integrating pointers. Since it is rather difficult to assure a simultaneous engagement of two coupling means, we prefer to effect an engagement of the pinion 119 with its associated gears prior to the engagement of the gear 123 with the crown gear 120. Such a sequence of operations can produce no error in the amounts depicted by the register, and is obtained by a system of levers which now will be described.

Referring more particularly to Figs 2, 3 and 5, the pinion 119 is mounted on a lever 127, which in turn rotates on a shaft 128. Movement of the pinion is controlled by a lever 129 which carries a pin 130 that projects into a relatively large recess 131 in the head of a pinion mounting bolt 132 (Fig. 5). A coil spring 133 surrounds the shaft 128 and has one arm engaging the bolt 132 and a second arm engaging the head of the pin 130 for biasing the pinion 119 in a counter-clockwise direction, as shown in Figs. 2 and 3. Movement of the lever 129 is controlled in turn partly through a slotted lever 134 which is pivotally mounted on a screw 135 which passes through a boss 136 provided on the lever 129. The slotted lever 134 carries at its pivot point a projection 137, about which a coil

spring is wrapped. One arm 138 of the coil spring engages a pin 139 attached to the slotted lever, and the other arm 140 of the spring engages the lower side of the shaft 128 and rests on a stationary lug 141. Two biasing actions are produced by this spring. The arm 138 tends to rotate the slotted lever 134 in a counter-clockwise direction, as shown in Figs. 2 and 3, until an extension of the pin 139 engages the upper surface of the lever 129. The long arm 140 of the spring acting through the projection 137 and the boss 136 tends to rotate the lever 129 in a clockwise direction, as shown in Figs. 2 and 3.

Actuation of the gear 123 also is effected through the slotted lever 134. For this purpose the slotted end of the lever 134 engages a pin 142 carried by an arm 143 fixed to a shaft 144 that carries a floating bearing 145 for the shaft 125. It should be noted that rotation of the shaft 144 rocks the bearing 145 to withdraw the gear 123 from the crown gear 120 or to engage said gears. In this way, the motor may be connected to the reset mechanism and may be disconnected therefrom. A stop pin 146 may be provided for cooperation with a stationary part of the register (not shown) for adjusting the movement of the gear 123 into contact with the crown gear 120. Movement of the arm 143 is restricted by means of a stop 147 which may be formed in the register face 10, if desired, and which engages a projection of the pin 142.

For actuating the levers thus far described, we provide a relatively rigid coil spring 148 which surrounds a screw 149 that is threaded into a tapped recess 150 provided in a stationary member 151. The stationary member also carries an adjustable pin 152 for providing an adjustable stop for the lever 127. The spring 148 has one arm positioned in a recess 153 provided in a push rod 154 while the other arm of the spring 148 bears against the slotted lever 134, as shown more clearly in Fig. 5. Consequently the coil spring constitutes a resilient bell crank connecting the slotted lever and the push rod 154.

When the push rod 154 is depressed inwardly, as shown in Fig. 2, the spring 148 tends to move the slotted lever 134 in a clockwise direction. Since the pin 142 in this figure is against its stop 147, the slotted lever 134 rotates about this pin as an axis and, therefore, rotates the lever 129 in a counter-clockwise direction. The counter-clockwise rotation of the lever 129 carries the pinion 119 into engagement with its associated gears 113 and 115, this engagement being somewhat resilient because of the action of the spring 133. The lever 129 is provided with two pins 155 and 156 which form a pocket adjacent the tip of the lever. The pin 156 may be conveniently formed by bending a lug on a plate 157 and passing the lug through an opening in the lever 129, the plate 157 and lever 129 being united by a rivet or by other suitable means. When the lever 129 is rotated as a result of the depression of the rod 154, the pin 156 is carried past the tip of a biased latching lever 158 which thereupon drops into the pocket formed by the pins 155 and 156 and holds the lever latched against return. The latching lever 158 conveniently may be biased by means of a weight 159, as shown, or by a spring and is mounted for rotation on a shaft 160. Normally, as shown in Fig. 1, the pins 156 and 155 are positioned within a recess 161 provided in the latching lever 158, but, as stated, rotation of the lever 129 carries the pin 156 past the latching edge of the latching

lever 158 which operates to hold the pinion 119 in engagement with its associated gears.

When the actuating rod 154 is released, the parts take the position shown in Fig. 3. Because of the action of the latching lever 158, the spring arm 140 cannot return the lever 129 to its original position. The spring arm 138, however, tends to return the slotted lever 134 towards its original position, but because the boss 136 about which this lever rotates has shifted, the slotted lever moves the arm 143 and shaft 144 in a clockwise direction and this movement brings the gear 123 into contact with the crown gear 120. Consequently, the integrating pointers 106 are connected to the demand indicating pin 104 and to the motor 50 which rotates the indicating pin toward its initial or zero position and simultaneously sets up on the integrating pointers an increased reading corresponding to the return movement of the indicating pin 104. In this return movement of the indicating pin, the sleeve 100 and arm 101 also are returned, and the pin 102 engages the pusher arm 20, if the latter is in an advanced position, and carries it to the zero position against the friction of the clutch. An adjustable stop 162 may be provided for determining the zero position.

As the arm 101 rotates in its return movement, it engages a pin 163 provided on the latching lever 158, and in the zero position rotates the latching lever sufficiently to free the lever 129. The lever 129 is promptly returned to its original position by means of the spring arm 140, and this movement not only moves the pinion 119 away from its associated gears, but through the slotted lever 134 carries the pin 142 against its stop 147. Since the displacement of the pin 142 is transmitted through the arm 143 and the shaft 144 to the bearing 145, the resultant rotation of the bearing carries the gear 123 out of engagement with the crown gear 120. Consequently, the mechanism is restored to its original condition.

If desired, one or more friction pads may be mounted on any of the shaft to resist undue movement thereof. As illustrated, the shaft 108 and 118 are provided with discs 164 against which felt or other friction pads 165 are urged by means of leaf springs 166. The tension of the springs 50 may be adjusted, if desired, by means of screws 167 which are threaded through stationary parts of the register.

Occasionally the push rod 154 may be depressed when the indicating pin 104 is at or near its zero position with a possible latching of the lever 129 in its reset position. To forestall such a possibility, we prefer to bias the latching lever 158 away from the lever 129 when the indicating pin is in its initial or zero position. This may be accomplished, for example, by mounting a leaf spring on either of the levers 101 or 158. As illustrated in Figs. 2 and 3, a leaf spring 168 is secured to a pin 169 which is mounted on the lever 158. The free end of the spring 65 normally is positioned slightly above the pin 163. During a resetting operation, as the arm 101 approaches its zero position it depresses the spring 168 against the pin 163 and releases the latching lever 158. After the release of the latching lever the spring 168 maintains the lever in its released position until the arm 101 clears the spring by rotating slightly in a clockwise direction. Therefore the resetting mechanism is ineffective when the indicating pin 104 is in its zero or initial position. If desired the spring

may be looped around the pin 163 which is notched as shown in Fig. 3a. The lip on the spring engages the pin for restricting the movement of the spring to any desired amount.

It is believed that the operation of the above-described apparatus is apparent. The gearing which drives the cam devices 64 and 72 is selected to provide any desired maximum demand interval which may be ten, thirty or sixty minutes. Over the billing period, the pin 104 is then advanced to a position corresponding to the maximum demand for any of these intervals. When the billing period has expired, this being usually of a month's duration, a meter reader will note the reading of the integrating pointers 106 and thereafter depress and release the actuating rod 154. Following such depression and release, the mechanism as above described returns the pin 104, arm 101, and pusher arm 20 to their initial or zero positions and the mechanism is thereupon available for another billing period. By subtracting the first reading of the integrating pointers from the new reading, the difference or maximum demand for the billing period is obtained.

If the register is enclosed within a sealed casing, a seal may be provided over the actuating rod 154 so that the operation of the actuating rod can be effected only by an authorized person. If desired, a cover may be provided with a depressible plunger which, when the cover is in position, overlies the actuating rod 154 so that depression of the plunger also depresses the actuating rod. The plunger may then be provided with suitable sealing means.

Although a clutch similar to that shown in the aforesaid patent may be employed for coupling the gear 24 to the sleeve 22, we prefer to employ the structure shown more particularly in Fig. 4. It should be noted that the clutch performs several functions. Not only must it engage positively enough for rotating the pusher arm 20 against the bias of the return spring, but it should release completely in order to permit the employment of a weak spring 28, and it should slip readily when engaged to facilitate the reset of the register at the end of a billing period.

In the assembly illustrated in Fig. 4, the pusher arm 20 is mounted on a hollow shaft or sleeve 22 preferably, though not necessarily, provided with an enlargement or head 200. This enlargement is releasably engaged by a plurality of equi-spaced fingers 201, three being a suitable number, which are pivotally mounted on a ring 202 and project through elongated slots 203 formed in a driving gear 24. A hub 204 not only supports the gear 24 on the shaft 25, but is provided with slots for receiving portions of the fingers 201. Preferably the ring 202 is a snap ring which snaps into a groove provided around the hub 204.

Actuation of the fingers 201 is effected through a sliding collar 206 which is provided with a cam portion 207 adjacent a releasing lug 208 on each of the fingers. The collar is biased by means of a coil spring 36 against an inclined portion 209 on each finger for forcing the fingers into frictional engagement with the head or enlargement of the sleeve 22. In this position the pusher arm 20 is actuated in accordance with the rotation of the watthour meter disc 2 against the bias of the spring 28. During a resetting operation, the pusher arm 20 may be actuated readily in the reverse direction, the frictional engagement of the fingers 201 with the sleeve 22 being sufficiently

small and uniform to permit a satisfactory reset of the mechanism.

When the clutch release arm 44 is actuated, the cam portion 207 engages the lugs 208 for releasing positively the fingers 201 from the sleeve 22. Because of the complete release of the clutch fingers, the spring 28 may be made weak enough to impose no undue burden on the watthour meter.

In assembling the structure shown in Fig. 4, preferably the hub 204 is secured to the shaft 25, as by making the hub a press fit thereon. A shoulder 25' on the shaft 25 may be employed for spacing the sleeves 22 and 100. Intermediate the ends of the sleeve 22 we prefer to reduce the cross-section of the shaft 25 for providing a clearance, the sleeve being supported at its ends on portions of the shaft of larger cross-section. The ends of the shaft 25 are mounted in suitable bearings.

A clutch of the type illustrated and described is disclosed more fully in application Serial No. 159,039, filed August 14, 1937.

The exact construction illustrated may, of course, be varied in many particulars. For example, instead of the integrating pointers 8 or 106, other registering mechanisms such as cyclometer dials or rotatable discs may be employed in their place. Since the maximum demand is obtainable from the pointers 106, an indicator, such as the pin 104, need not be employed. Ordinarily it is desirable to include the indicator. Although we have illustrated a hysteresis type of motor 50, other constant speed motors or clock-work mechanisms may be employed as desired and separate motors may be employed for interval timing and resetting operations. The gear couplings 113, 115, 119 and 120, 123 may be replaced by any suitable clutch units.

Since our invention is capable of many modifications, we do not desire to be restricted to the specific embodiments illustrated and described. Therefore, our invention is to be restricted only by the appended claims as interpreted in view of the prior art.

We claim as our invention:

1. In an instrument, a member movable to a position corresponding to the demand measured by said instrument for a predetermined period, means for actuating said member including a releasable clutch, electromotive means for restoring said member against the resistance of said clutch to a predetermined setting, and means for restoring said member to said predetermined setting including means for releasing said clutch.

2. In an instrument, a member movable to a position corresponding to a quantity measured for a predetermined period, means for actuating said member including a releasable clutch, an element for actuation by said member to a position corresponding to the maximum movement of said member during a predetermined period, electromotive means for restoring said member and element to predetermined positions against the resistance of said clutch, and means for restoring said member to a predetermined position including means for releasing said clutch.

3. In an instrument, an indicator, means for actuating said indicator, a friction coupling between said means and said indicator, means for biasing an element of said friction coupling towards a predetermined position, electromotive means for resetting said indicator to a predetermined position against the resistance of said

friction coupling, and means for periodically releasing said friction coupling.

4. In a maximum demand indicator reset, an indicator, an actuating member and means responsive only to both movement away from an initial position and return of said member for initiating a resetting of said indicator.

5. In an instrument, a member movable in accordance with a variable quantity, indicating means, a first means for coupling said member to said indicating means, motive means, a second means for coupling said motive means to said member, and means for actuating both of said coupling means, said means actuating said second coupling means subsequent to actuation of said first coupling means.

6. In an instrument, indicating means, and means for actuating said indicating means including a plurality of coupling means, a control member, means responsive to movement of said control member in a first direction for actuating a first one of said coupling means, and means responsive to movement of said control member in a second direction for actuating a second one of said coupling means.

7. In an instrument, a movable member capable of remaining in a position to which it is moved, electromotive means for restoring said movable member to a predetermined position, a latch device for maintaining said electromotive means operatively connected to said movable member, said latch device being released in response to the arrival of said movable member at a predetermined position for interrupting said operative connection.

8. In a control system for an instrument, a first lever, a first releasable coupling means controlled by said first lever, a pivot carried by said first lever, said first lever being movable into and away from a position wherein said coupling means is engaged, latching means for holding said first lever in said position, a second lever mounted on said pivot, a second releasable coupling means controlled by said second lever, said second lever being free for engaging said second coupling means only when said first lever is in a predetermined position.

9. In an instrument, a movable operating member, a spring having a projecting arm positioned for movement by said operating member, said spring being rotatable about an axis positioned at an angle relative to the direction of movement of said operating member, an operated member, and a second projecting arm on said spring for operating said operated member.

10. In an instrument, an element movable in accordance with a variable quantity, register means for registering movements of said element, a first transmission member movable in accordance with movements of said element, a second transmission member movable in accordance with movements of said register means, and a third transmission member for coupling said first and second transmission members, said third transmission member being movable into and out of effective bridging relationship relative to said first and second transmission members.

11. In an indicator reset mechanism, an indicator, a first gear operatively connected to said indicator, a register, a second gear operatively associated with said register, said gears being mounted on parallel, aligned shafts, and separate coupling gear means rockable into and out of effective bridging relationship relative to said first and second gears.

12. In a register, a maximum demand indicator, a first transmission member driven in accordance with said indicator, a register, a second transmission member driven in accordance with said register, a third transmission member for coupling said first and second transmission members, said third transmission member being yieldably biased in engagement with said first and second transmission members and movable for interrupting said coupling, a motive device, and transmission means between said motive device and one of said first two transmission members, said transmission means including a releasable coupling and means operative after movement of said third transmission member to its engaged position for urging said coupling into its transmitting position.

13. In an instrument, a control device for resetting said instrument to a predetermined condition after a departure therefrom, latching means for maintaining said control device in operative position, release means for releasing said latching means after a resetting operation, and means for preventing premature movement of said latching means to latching position while said instrument is in said predetermined condition.

14. In a register reset, a member movable to a position corresponding to a variable quantity, means for restoring said member to a predetermined setting, and means for preventing actuation of said restoring means until said member has departed appreciably from said predetermined setting.

15. In a demand instrument, a member movable to a position corresponding to a variable quantity, means for resetting said member to a predetermined position, a latching lever for maintaining said resetting means in operation, said latching lever being operable by said member as it approaches said predetermined position for releasing said resetting means, and a spring element interposed between said member and said latching lever for providing a resilient engagement therebetween when said member is in its predetermined position.

16. In a maximum demand instrument having a movable member and means for moving said movable member from an initial position to a position corresponding to the maximum demand for any desired interval, a source of power, a movable lever, means controlled by the position of said lever for operatively connecting said source of power to said movable member for restoring said movable member to said initial position, latching means for holding said lever in source-connecting position, and means effective on arrival of said movable member in said initial position for tripping said latching means.

17. In a maximum demand instrument having a maximum demand cumulative register, a movable member and means for moving said movable member from an initial position to a position corresponding to the maximum demand for any desired interval, a source of power, a movable lever, means controlled by the position of said lever for operatively connecting said source of power to said movable member for restoring said movable member to said initial position and to said register for summing the maximum demands occurring between restorations of said movable member, latching means for holding said lever in source-connecting position, and means effective on arrival of said movable mem-

ber in said initial position for tripping said latching means.

18. In a cumulative maximum demand device having a member movable from an initial position to a position corresponding to the maximum demand for a predetermined interval, a first gear connected for movement in accordance with the movement of said movable member, a register having an actuating gear, a lever movable between a first location and a second location, coupling means controlled by said lever for coupling said two gears when said lever is in its first location and for uncoupling said two gears when said lever is in its second location, motive means, and transmission means for coupling said motive means to said first gear for moving said movable member to its initial position, said transmission means including a releasable coupling engageable only when said lever is in its first location.

19. In a cumulative maximum demand device having a member movable from an initial position to a position corresponding to the maximum demand for a predetermined interval, a first gear connected for movement in accordance with the movement of said movable member, a register having an actuating gear, a lever movable between a first location and a second location and biased towards said second position, latching means for holding said lever in its first location, means effective when said movable member is in its initial position for tripping said latching means, coupling means controlled by said lever for coupling said two gears when said lever is in its first location and for uncoupling said two gears when said lever is in its second location, motive means, and transmission means for coupling said motive means to said first gear for moving said movable member to its initial position, said transmission means including a releasable coupling engageable only when said lever is in its first location.

20. In a cumulative maximum demand device having a member movable from an initial position to a position corresponding to the maximum demand for a predetermined interval, a first gear connected for movement in accordance with the movement of said movable member, a register having an actuating gear, a lever movable between a first location and a second location, coupling means controlled by said lever for coupling said two gears when said lever is in its first location and for uncoupling said two gears when

said lever is in its second location, motive means, actuating means for moving said lever into its first location, and means effective only when said actuating means is operated in one direction for moving said lever into its first location and then is operated in a second direction for coupling said motive means to said first gear, the coupling of said motive means to said first gear being effective for moving said movable member towards its initial position.

21. In a cumulative maximum demand device having a member movable from an initial position to a position corresponding to the maximum demand for a predetermined interval, a first gear connected for movement in accordance with the movement of said movable member, a register having an actuating gear, said first gear and said actuating gear being mounted for rotation about a common axis, a lever movable between a first location and a second location, coupling gear means controlled by said lever for coupling said two gears when said lever is in its first location and for uncoupling said two gears when said lever is in its second location, motive means, and transmission means for coupling said motive means to said first gear for moving said movable member to its initial position, said transmission means including a releasable coupling engageable only when said lever is in its first location.

22. In a cumulative maximum demand device having a member movable from an initial position to a position corresponding to the maximum demand for a predetermined interval, a first gear connected for movement in accordance with the movement of said movable member, a register having an actuating gear, a lever movable between a first location and a second location, coupling means controlled by said lever for coupling said two gears when said lever is in its first location and for uncoupling said two gears when said lever is in its second location, motive means, transmission means for coupling said motive means to said first gear for moving said movable member to its initial position, said transmission means including a releasable coupling, and a second lever pivoted on said first-named lever for controlling said releasable coupling, said second lever being operable for engaging said releasable coupling only when said first-named lever is in its first location.
